ELECTRIC SELF WINDING DEVICE

Filed Sept. 26, 1927

UNITED STATES PATENT OFFICE

USHICHIRO TOKUMI, OF NEW YORK, N. Y.

ELECTRIC SELF-WINDING DEVICE

Application filed September 28, 1927. Serial No. 222,189.

This invention relates to electrically actuated winding devices for use in connection with apparatus of various kinds and classes, such for example as clocks, watches, time 5 pieces and the like; and the object of the invention is to provide an improved switch member for devices of the class specified consisting of a comparatively light tensioned spring arm having two parts movable relatively to each other, and between which parts an electric conductor or finger is adapted to pass, tensionally engaging both parts of the switch arm to close the circuit to the electrical mechanisms of the device; a further object 10 being to provide an electromagnet with means for mounting the same in connection with a support or clock movement, and a member carrying electromagnetic shoes movable relatively to the opposite end portions of said 15 magnet, and swinging in its movement on an axis centrally of the core of the electromagnet, said member carrying at one end, a contact finger movable relatively to said switch, and means at the other end or cooperating 20 with the other end of said member for moving the same in a direction opposite to the movement imparted thereto by the electromagnet, and for actuating or winding the mechanisms coupled with said member in this 25 movement; and with these and other objects in view, the invention consists in a device of the class and for the purpose specified, which is simple in construction, efficient in use, and which is constructed as hereinafter described 30 and claimed.

The invention described and claimed herein is an improvement on that shown and described in an application for letters patent of the United States, filed by me June 11, 40 1927, and bearing Serial Number 198,069, and is fully disclosed in the following specification, of which the accompanying drawing forms a part, in which the separate parts of my improvement are designated by suitable 45 reference characters in each of the views, and in which:—

Fig. 1 is a diagrammatic side view of a part of a clock movement, showing my improved 50 device mounted in connection therewith.

Fig. 2 is a face view of the construction shown in Fig. 1; and,

Fig. 3 is a detail view, illustrating parts of a switch device in several positions.

In the drawing, 5 and 6 represent the frame 55 plates or members of a clock or other time piece. At 7, I have shown one of the shafts of the time piece which may constitute any shaft for driving the mechanisms of the time piece by my improved device. On this 60 shaft, is a gear 8 rotated by the action of an operating member 9, consisting of side plates 9a and 9b, rotatable on the shaft 7, the plate 9b carrying a pawl which engages with the gear 8.

The side plates 9a and 9b of the member 9 are joined at their ends by arc-shaped shoes 11 and 12, which are adapted to move into alinement with the opposite ends of the core 13 of an electromagnet 14, which magnet is 70 supported in connection with the frame 5 of the time piece in the construction shown by a strap or other member 15, and by screws or bolts 16 and 17 passed through the ends of the core 13. The screw 16 constitutes a 75 terminal for a wire 19 extending from the windings 20 of the electromagnet, thus grounding said wire to the frame 5 and to the member 9. A wire 21 from a source of electric supply extends to the windings 20 where- 80 as the other wire 22 from said source of supply extends to a terminal 23 on a switch device 24 which I employ.

The upper end of the member 9 or the end to the left as seen in Fig. 2 of the drawing, 85 carries a contact finger 25 which projects beyond the end of the member 9 and the shoe thereof, whereas the other end of the member 9 carries a projecting rod 26 on which is adjustably mounted a weight 27 which is adapt- 90 ed to rotate the member 9 on the shaft 7 in a clockwise direction as seen in Fig. 2 of the drawing to actuate and rotate the gear 8 through the pawl 10 to operate the clock or other apparatus until the member 9 reaches 95 the position shown in Fig. 2 of the drawing. From this position, it is moved into a position to raise the weighted end of the mem- 100 ber 9 by the action of the electromagnet 14, drawing the shoes 11 and 12 into alinement

with the ends of the core 13 of said magnet. This operation is controlled by the switch 24.

The switch 24 is supported upon a block 28 on the frame 5, said block being composed of insulating material, or the switch being insulated from said block. The switch, in the construction shown, consists of two curved spring arms 29 and 30, the ends of both of which are fixed to the block 28 and are in circuit with the wire 22. The arm 29 is continuous in its arc-shaped formation and provided at its free end with a contact point 31, upon which the contact finger 25 strikes in the operation of the device and in closing the circuit, which puts the electromagnet into operation.

The arm 30 of the switch has an offset portion 32 centrally thereof to form a recess 33 through which the contact finger 25 is adapted to pass in the automatic movement of said finger out of engagement with the switch. The outer end of the arm 30 carries on one face thereof, namely the outer face with reference to the arm 29, a sheet of insulating material 34 on which is a metallic sheet 35 which forms a bearing sheet over, which the contact finger 25 passes in the operation of the device. The sheet 35 is merely to take up the wear and is out of circuit with or insulated from the arm 30. It will also be seen that the arm 30 is shorter than the arm 29 to provide for the passage of the switch 25 over the end of the arm 30 and onto the arm 29 in the operation of the device.

The contact finger 25 travels in a straight vertical path with reference to the switch 24 or the separate arms 29 and 30 thereof, said arms normally assuming a position such as is indicated in dotted lines in Fig. 3 of the drawing so that the arm 29 is placed under tension when it engages the contact 25 as seen in Figs. 1 and 2, and both of the arms 29 and 30 are placed under tension as seen in full lines in Fig. 3 of the drawing as the contact finger 25 descends through and between the adjacent faces of the arms 29 and 30. When it reaches the recess 33, the spring tendency of the arms and especially the arm 30 which has been placed under tension, will move said arms out of the upward path of the contact 25 sufficiently to allow said contact finger to strike the outer surface or plate 35 of the arm 30 in its upward movement, thus forcing both arms to the left until the said finger rides over the free edge of the arm 30 and engages the point 31 on the arm 29.

It will be understood that in the operation of the device, the instant the contact finger 25 strikes the contact point 31, the circuit through the wires 21 and 22 will be completed, and the electromagnet energized, which will operate to move the shoes 11 and 12 into a position in longitudinal alinement with the ends of the core 13 and bring the finger 25 into the dotted line position indi-

cated in Fig. 2 and raise the weight 27 at the right hand end of the member 9 which will then be extended upwardly. This movement is very quick and takes but a fraction of a second, due to the action of the electromagnet. When the member 9 is in the last named position, the switch returns to the dotted line position indicated in Fig. 3 of the drawing out of engagement with the contact finger 25 and the electric circuit through the wires 21 and 22 is again broken and the operation of the clock movement or other apparatus or mechanism continues by the downward movement of the right hand end of the member 9 by virtue of the weight 27, it being understood that the weight is sufficient to operate the clock movement or other mechanism, and the electromagnet will be sufficiently powerful to raise the weight and move the member 9 into its operative position against the action of gravity.

It will also be understood that my invention is not necessarily limited to the specific details of construction herein shown and described in the several parts of my improved device, or the manner of their mounting, one of the distinctive features of my invention residing in the particular type of switch device herein shown and described, and various changes in and modifications of the construction herein set out may be made within the scope of the appended claims, without departing from the spirit of my invention or sacrificing its advantages.

Having fully described my invention, what I claim as new and desire to secure by Letters Patent, is:—

1. The combination with a reciprocating electric contact member in one side of an electric circuit, of a spring contact in the other side of said circuit and arranged in the path of the reciprocating movement of said first named contact, means whereby in one position of the first named contact relatively to the spring contact, said circuit will be maintained closed, and in other positions of said contact said circuit will be maintained in open position, means in said electric circuit for actuating said first named contact in the first named position, means independent of said circuit for moving said contact in its second named position, and said spring contact involving two spring arms between which the reciprocating contact passes in the first named movement thereof.

2. The combination with a reciprocating electric contact member in one side of an electric circuit, of a spring contact in the other side of said circuit and arranged in the path of the reciprocating movement of said first named contact, means whereby in one position of the first named contact relatively to the spring contact, said circuit will be maintained closed, and in other positions of said contact said circuit will be maintained in

- open position, means in said electric circuit for actuating said first named contact in the first named position, means independent of said circuit for moving said contact in its second named position, said spring contact involving two spring arms between which the reciprocating contact passes in the first named movement thereof, and an insulated surface on one of said arms over which said reciprocating contact passes in the second named movement thereof. 5
3. In combination, two electric contacts, one of said contacts being in one side of an electric circuit and the other in the other side of said circuit, one of said contacts having spring properties and the other contact having non-yielding properties, one of said contacts being movable intermittently with respect to the other whereby in one movement thereof, the circuit through said contacts will be closed and in the other movement thereof, the circuit through said contacts open, means in said electric circuit for actuating one of said contacts to cause said first- 10 named movement, and means independent of said circuit for actuating the same contact to cause said other movement, said spring contact being composed of independent members between which the other contact is disposed when the circuit is completed through said contacts and one of said members having an insulated surface, over which the non-yielding contact passes when the circuit is open through said contacts. 15
- 35 4. The combination with a reciprocating, electric contact member in one side of an electric circuit, of a spring contact in the other side of said circuit and arranged in the path of the reciprocating movement of said first named contact, said spring contact involving a relatively long, yielding, member, one side of which has a conducting surface and the other side of which has an insulated surface, said first named contact being movable over both surfaces of said yielding member, completing said electric circuit throughout its contact with said conducting surface, and maintaining said circuit open in its movement over the insulated surface, means in said electric circuit for actuating said first-named contact to cause its circuit-closed movement, and means independent of said circuit for actuating the same contact to cause said circuit-open movement, and said spring contact involving another resilient contact member, movable relatively to the first named member and between which and the conducting surface of the first named member, said first named contact passes in completing said electric circuit. 20
5. The combination with an electric contact having yielding properties arranged in one side of an electric circuit, said contact having a conductor surface and an insulated surface, of an electric contact in the other side of said circuit and adapted to reciprocate relatively to said yielding contact and movable over the conductor surface thereof in one directional movement in maintaining said electric circuit closed and over the insulated surface in the other directional movement thereof in maintaining said electric circuit open, means in said electric circuit for actuating said second-named contact to cause its circuit-closed movement, and means independent of said circuit for actuating the same contact to cause said circuit-open movement, and another yielding contact in circuit with said first named contact and movable with and relatively to the conductor surface of said yielding contact and in connection with which said reciprocating contact operates. 25
6. The combination with a yielding contact in one side of an electric circuit and involving elongated contact parts, one of which is of greater length than the other, and said parts being movable relatively to each other, of a contact in the other side of said circuit and intermittently movable longitudinally with respect to the parts of said first named contact, maintaining said electric circuit closed in its movement between said parts in one stroke of said reciprocating contact and movable over an insulated surface on one of said parts, maintaining said circuit open during the other stroke of said reciprocating contact, means in said circuit for actuating said second-named contact to cause said first stroke, and means independent of said circuit for actuating the same contact to cause said second stroke, and said reciprocating contact engaging the long part of said yielding contact at the completion of the last named stroke thereof to complete said circuit at the termination of said stroke. 30
- In testimony that I claim the foregoing as my invention I have signed my name this 24th day of Sept., 1927.
- USHICHIRO TOKUMI.
